Primary Examiner — Bao-Yen T Nguyen(74) *Attorney, Agent, or Firm* — Greenberg Traurig, LLP(57) **CLAIM**

The ornamental design for a display screen with graphical user interface, as shown and described.

DESCRIPTION

The FIGURE is a front view of a display screen with graphical user interface showing my new design.

The broken lines of uneven length show the display screen and form no part of the claimed design. The remaining broken lines form no part of the claimed design.
